UNITED STATES PATENT OFFICE.

HENRY FISHER, OF ALLIANCE, OHIO.

IMPROVEMENT IN MOWING-MACHINES.

Specification forming part of Letters Patent No. 32,214, dated May 7, 1861.

To all whom it may concern:

Be it known that I, HENRY FISHER, of Alliance, in the county of Stark and State of Ohio, have invented certain new and useful Improvements in Grass-Harvesters; and I do hereby declare that the following is a full, clear, and exact description of the same, reference being had to the accompanying drawings, making part of this specification, in which—

Figure 1 is a perspective view of a machine embodying my said improvements, and Fig. 2 a vertical section at $x x$.

Similar letters of reference indicate corresponding parts in both figures.

The improvements relate, first, to a combination of devices for controlling the machine, increasing the traction of the driving-wheel, holding the cutter-bar to its work, and elevating it over obstructions when needful; second, to an improved lock-joint on the outer end of the finger-bar.

A is the driving or ground wheel, carrying a cogged ring, B, which imparts motion to the cutter-bar C through the medium of pinion D, shaft E, gearing F G, crank-wheel H, yoke I, and connecting-rod J.

The draft-frame K is attached adjustably to standards L L, projecting above the axle a of the driving-wheel.

M M' are handles secured in front to the axle a , and at their centers attached adjustably to standards N, rising from the rear part of the frame, so as to admit of setting the handles at any height to suit the convenience of the operator.

O is a wheel running on an adjustable axle, and supporting the heel of the finger-bar P at any desired height.

S is a caster-wheel supporting the finger-bar toward its outer end when removing the machine from place to place.

Q is a track-clearer pivoted at q , and clamped at any desired height by means of a clamp-screw, q' , working in a slot, q'' . The said track-clearer is formed on its upper side with a sharp edge, q^3 , (which may be serrated, scalloped, or smooth,) for the purpose of cutting lodged clover, pea-vines, or other stuff which may come upon it, as well as performing the other functions of the common track-clearer.

T is the shoe, which supports the outer end

of the finger while in operation. The manner of securing the shoe and the track-clearer upon the finger-bar is shown in Fig. 2.

The end of the finger-bar is made straight, and is, by means of a screw, U, tightly clamped between the track-clearer Q and shoe T, the latter being formed with vertical flanges t and t' , which firmly support the finger-bar and track-clearer at the side and rear.

The whiffletree R is bolted to the draft-frame K by any one of the holes k to regulate the side draft.

The connecting-rod J and cutter C are so arranged and attached that by removing the bolt which connects them and taking off the wheel O the cutter is left free to be drawn out without displacing any other part of the machine.

It will be observed that the attachment of the draft-frame K to the standard L above the axle of the driving-wheel tends to throw the weight of the finger-bar, &c., on the driving-wheel, and thus increase its traction. This weight is increased, when needful, by pressure upon the handles M M'. By means of the handles the finger-bar may be readily raised over any obstruction when needful—an action which does not materially change the position of the draft-frame and whiffletree.

By the use of handles the machine is placed more fully under the control of the operator, the horse is relieved from the labor of drawing so much additional weight, and the operator subjected to less danger of injury.

The present illustration represents a machine adapted for a single horse. In those of large size two or more horses are of course employed, while by reducing the size of the machine and adding a handle in front the machine is well adapted for a hand or lawn mower. By dispensing with shaft and tongue the finger-bar is left free to yield slightly to any sudden obstruction, which might otherwise strain or break it.

I am aware that a crank-wheel and slotted yoke have previously been used to transmit the required reciprocating motion to the cutter; but I know of no previous instance in which such slotted yoke has been applied to a pivoted connecting-rod in the manner herein shown and described to transmit motion to a movable cutter from a crank-wheel rotating in a plane oblique to that of the cutter.

What I claim as new, and desire to secure by Letters Patent, is—

1. The combination of the projecting standards L L and adjustable pivoted handles M M', when used in connection with a finger-bar, P, located in the rear and extending on one side of the driving-wheel A, all as herein shown and described, and for the purposes explained.
2. The lock-joint at the outer end of the fin-

ger-bar, formed of the shoe T, flanges t t', track-clearer Q, and screw U, constructed and applied in the manner and for the purposes explained.

HENRY FISHER.
